UNITED STATES PATENT OFFICE

2,433,040

MACHINE FOR DIE CURLING CAN END FLANGES

William J. Geist, St. Louis, Mo., assignor to Continental Can Company, Inc., New York, N. Y., a corporation of New York

Application July 18, 1945, Serial No. 605,795

2 Claims. (Cl. 153—34)

1

The invention relates to new and useful improvements in a machine for curling the flange of a can end preparatory to the seaming of the end to a can body.

An object of the invention is to provide a machine wherein the can end flange may be curled by dies moving radially of the can end and in the plane of the can end flange.

A further object of the invention is to provide a machine of the above type wherein the portion of the flange which is to be curled is bent at an angle to the plane of the flange preparatory to the die curling of the same.

These and other objects will in part be obvious and will in part be hereinafter more fully disclosed.

In the drawings which show by way of illustration one embodiment of the invention:

Figure 1 is a vertical sectional view through a portion of the machine at the curling station and at right angles to the line of feed of the ends to the curling dies;

Figure 2 is a vertical sectional view through a portion of the machine on a line parallel with the line of feed;

Figure 3 is an enlarged detail of a portion of the curling head showing the operating mechanism for one of the die sections;

Figure 4 is a detail showing in part the chuck, the curling die, the bending ring and the position of the can end when fed beneath the curling head;

Figure 5 is a similar view but showing the can end lifting pad raised into contact with the end and the end forced into the bending ring;

Figure 6 is a view similar to Figure 5 but showing the can end forced all the way through the bending ring and into engagement with the chuck and the curling dies with the dies retracted;

Figure 7 is a view similar to Figure 6 but showing the dies as having moved inwardly for curling the flange;

Figure 8 is an enlarged view of a portion of the end as fed to the improved curling dies;

Figure 9 is a similar view but showing the portion of the flange which is to be curled bent at an angle to the plane of the flange as a preliminary to the curling of the flange;

Figure 10 is a similar view showing the flange curled.

The invention has to do with a machine for die curling the flange of a can end preparatory to the securing of the can end flange to a can body. In Figure 8 of the drawing a can end 1 is shown in part, which includes a central depressed portion

2

surrounded by a vertical wall 2 from which projects a horizontal flange 3. This end is formed from a body blank by dies. In order that the end may be secured to a can body by rolling the flange of the end into contact with the body wall, it is desirable that this flange at the outer peripheral edge thereof shall be curled, as indicated at 4 in Figure 10, and that the curl be embedded in the body wall.

10 The present invention has to do with a machine for die forming this curl 4 at the edge portion of the flange 3 of the can end 1. The can ends are fed one at a time beneath a die curling head. Associated with this die curling head is a bending ring. The end is lifted from its support into contact with the bending ring, and forced through the bending ring, which operates to turn the portion of the flange which is to be curled downward at an angle to the plane of the flange, as indicated at 5 in Figure 9. The end with this preliminary bend 5 is then placed on a chuck and segmental dies are moved inwardly. The dies engage this bent edge portion and form it into the curl, as shown at 4 in Figure 10.

15 25 The can ends 1 are fed one at a time along a support 6 by a feed bar carrying feed dogs 7. Immediately underneath the curling head 8 are can end supporting members 9, 9. These supporting members move at right angles to the line of feed of the can ends. In Figure 1 they are shown at the inner position of movement. These supporting members are moved into the position stated by springs 10, 10. The can ends are fed along the support 6 onto these supporting members 9, 9.

30 35 The curling head 8 includes a stationary supporting member 11 carrying a chuck 12. Beneath the chuck 12 is a bending ring 13 or female die-shaping member. Just above the bending ring are segmental dies 14, 14. The machine is particularly adapted for curling the flange on an end which is to be seamed to a can body having flat sides and rounded corners. The curling dies and the operating means therefor is very similar in

35 40 45 construction and operation to the curling dies shown in my copending application Serial No. 495,201, filed July 17, 1943, and, therefore, it will only be necessary to describe very briefly the means for moving these segmental dies radially of the curling head.

45 50 The curling dies are supported on the bending ring so that they can move freely radially of the chuck. Each curling die has an inwardly projecting portion 15 which is adapted to operate 55 in a groove 16 in the chuck 12. The curling die

has a flat portion 17 which terminates in a curved portion 18 which operates upon the flange of the end for the curling of the same. The outer ends of the segmental dies are inclined as indicated at 19. A cam ring 20 is provided with a cam face 21 which is adapted to engage the inclined face 19 on the dies for forcing the same inwardly when the ring 20 is lowered.

Pivoted to the stationary head 11 are levers 22. Each lever is pivoted at 23 and is provided at its lower end with a projecting nose 24, which extends into a slot 25 in the die segment. Associated with the cam ring 20 is an inwardly projecting plate 26 which is adapted to engage a curved cam surface 21 on each of the levers 22. The cam ring 20 is carried by rods 28 which are reciprocated by suitable means and when the cam ring moves upwardly, this plate 26 will engage the levers 22 and will retract or move outwardly the segmental dies. These segmental dies are therefore positively moved inward by the cam ring 20 engaging the inclined face 19 on the die segments and are positively moved outward by the plate 26 engaging the cam face of the levers. It will be understood that there are a series of these levers and the operation is practically the same as that shown and described in my copending application.

Immediately below the die curling head is a lifting pad 29. Associated with this lifting pad is a male die member 30. The lifting pad is mounted in a plunger 31 which is raised and lowered by means of a cam 32. The lifting pad support rests on a spring 33 and the extent to which the lifting pad is moved upwardly in the plunger is limited by a pin 34 engaging a slot in the plunger.

The male die member 30 is carried by a sleeve 35 mounted for reciprocation in a supporting member 36. The sleeve is connected to a bracket member 37 carrying a roller 38 cooperating with a cam 39. The plunger reciprocates in the sleeve as a bearing therefor.

After the end has been placed on the supports 9, 9 the lifting pad 29 and die 30 are simultaneously raised so as to engage the can end. The male die member is provided with cam faces 40, 40. These cam faces engage inclined faces 41, 41 on the can end supports 9, 9. The upward movement therefore of the die will force these supports 9, 9 away from each other and permit the projecting portion 42 of the male die member 30 to lift the end and force it into the bending ring 13, as shown in Figure 5. The die member only moves into the ring to a limited extent but sufficient to cooperate with the bending ring in the die-shaping of the downwardly bent portion 5 on the can end.

The cam 32 is so shaped that the lifting pad carries the can end all the way through the ring and places the same on the chuck 12. When the end is fully seated on the chuck, the upper face of the flange of the end will contact with the under face 17 of the segmental dies. The operating means for the cam ring 20 now comes into action and forces the segmental dies inwardly, forming the bent end 5 into the curl 4, as shown in Figure 7. After completing the curl the segmental dies are retracted, the lifting pad moved down, and the end will move down therewith until it is positioned as shown in Figure 2.

Mounted on the feed bar is a feed dog 43. This feed dog is pivoted at 44 to the feed bar and is lifted by means of a spring so that the shoulder 45 on the feed dog will engage the can end and

this will move the can end to the right, as viewed in Figure 2, pulling the end from beneath the head. At the same time the feed dog 7 will engage the next end and move it beneath the head, ready for the next curling operation.

It is believed that the operation of the machine has been described in detail sufficient for an understanding of the same. While the machine has been described as especially adapted for the curling of a flange on an end having flat sides and rounded corners, it will be understood that the machine can be readily adapted for curling ends of other shapes. When the flange is curled, the overall diameter of the end is reduced so that the end will drop freely through the bending ring and be removed from beneath the head by the feeding mechanism.

It is obvious that many changes in the details of construction and arrangement of the parts may be made without departing from the spirit of the invention as set forth in the claims.

I claim:

1. A machine for curling the flanges of can ends comprising means for supporting a flanged can end, a chuck disposed directly above said supporting means, reciprocating curling dies associated with the chuck and movable radially thereof, a bending ring disposed beneath the chuck and spaced therefrom, a male die for lifting the end from its support and forcing the same into the ring whereby the edge portion of the flange is bent at right angles thereto, and a lifting pad associated with the male die for carrying the end through the ring into engagement with the chuck and into range with the reciprocating dies a means operating in timing with the lifting means for moving the curling dies into engagement with the bent portion of the flange for forming a curling therein.

2. A machine for curling the flanges of can ends comprising a chuck, reciprocating curling dies associated with the chuck and movable radially thereof, radially movable devices beneath the chuck for supporting the can end by the flange thereof and for centering said can end beneath the chuck, a spring means for moving said devices inwardly, a bending ring disposed between said chuck and said can end supporting devices, a male die for lifting the end from its supporting devices and for forcing the same into the bending ring whereby the edge portion of the flange is bent at right angles thereto, a lifting pad associated with the male die for carrying the end through the ring into engagement with the chuck and into range with the reciprocating dies and means operating in timing with the lifting pad for moving the curling dies into engagement with the bent portion of the flange for forming a curl therein.
